UNITED STATES PATENT OFFICE.

DANIEL N. MEANY, OF CHICAGO, ILLINOIS.

DESIGN FOR A FIREPLACE GRATE.

Application filed July 28, 1922. Serial No. 3,232. Term of patent 3½ years.

To all whom it may concern:

Be it known that I, DANIEL N. MEANY, a citizen of the United States, residing at Chicago, in the county of Cook and State of Illinois, have invented a new, original, and ornamental Design for a Fireplace Grate, of which the following is a specification, reference being had to the accompanying drawing, in which a perspective view of the fireplace grate is shown.

I claim:—

The ornamental design for a fireplace grate, as shown.

In testimony whereof I affix my signature.

DANIEL N. MEANY.
